UNITED STATES PATENT OFFICE.

CHARLES D. YOUNG, OF ALTOONA, PENNSYLVANIA.

BRAKE-SHOE.

1,124,379.

Specification of Letters Patent.

Patented Jan. 12, 1915.

Application filed April 11, 1913. Serial No. 760,474.

To all whom it may concern:

Be it known that I, CHARLES D. YOUNG, a citizen of the United States, residing at Altoona, in the county of Blair and State 5 of Pennsylvania, have invented certain new and useful Improvements in Brake-Shoes, of which the following is a specification.

The invention relates to brake shoes having a cast body and a wrought back. The 10 invention has for its primary objects the provision of an improved type of wrought metal back, and one which can be produced from sheets of metal such as sheet steel, with a minimum of scrap. One embodiment of 15 the invention is illustrated in the accompanying drawings, wherein—

Figures 1 and 2 are plan and side elevation views respectively of the shoe, with the embedded portions of the back indicated in 20 dotted lines, Figs. 3 and 4 are transverse sections on the lines III—III and IV—IV respectively of Fig. 2, and Fig. 5 is a plan view of a sheet of metal, showing the method of cutting out the backs without waste.

The wrought metal back is preferably in 25 the form of an **H** as indicated in Fig. 5, such **H** comprising the legs 1, 1, 1, 1, the cross bar 2, and the extensions of such cross bar, 3, 3, such extensions projecting out past 30 the side edges of the legs. The legs 1, 1, 1, 1, are embedded in the body portion 4 of the shoe by placing the wrought back in the mold and casting the body portion 4 in the usual way.

As indicated in Figs. 1 and 2, the lug 35 is formed by the cross bar 2, the ends of the legs 1 adjacent such cross bar being bent up as indicated in Fig. 2. The extensions 3, 3, at the ends of the cross bar are bent down 40 as indicated in Figs. 2 and 3, thus providing additional metal and greater stiffness in the lug.

The legs 1, 1, 1, 1, instead of being left flat 45 are bent into curved cross section as indicated in Fig. 4, the central portion of each leg coming flush with the top of the cast metal of the shoe, while the edge portions are embedded securely in the body of the shoe. This arrangement gives the legs additional stiffness, and embeds them more 50 securely in the cast metal.

The method of cutting the blanks from a sheet of steel in order to avoid waste, is in-

dicated in Fig. 5. It will be noted that the backs interfit in such manner that there 55 is substantially no waste material. This is due to the fact that the distance A between two legs of the **H** is substantially equal to the width B of one of the legs, so that the metal between the legs is not wasted, but 60 is formed into the leg of another back. Similarly by making the length C of the extension 3 equal to substantially one-half the width of the leg, waste material is avoided at this point. It will be seen that this 65 would not be the case if the length C of the extensions were greater or less than half the width of one of the legs.

What I claim is:

1. In combination in a brake shoe, a cast 70 body portion, and a wrought back of **H** form having the legs thereof embedded in the body portion and the cross bar bent up to form a lug, the ends of the cross bar being extended past the outside edges of 75 the legs and bent down at right angles to the body portion of the cross bar.

2. In combination in a brake shoe, a cast 80 body portion, and a wrought back having its end portions embedded in the body portion and having its central portion bent up in **U** form to provide a lug, the upper portion of the lug having its side edges extended out past the side edges of the back and bent down partially closing the opening through 85 the lug.

3. A wrought brake shoe back of sheet 90 metal in the form of an **H** with the bar of the **H** extended out laterally past the side edges of the legs.

4. A wrought brake shoe back of sheet 95 metal in the form of an **H** with the space between the legs substantially equal to the width of one of the legs and with the bar of the **H** extended out laterally past the side edges of the legs a distance equal substantially to one-half the width of one of the legs.

In testimony whereof I have hereunto signed my name in the presence of the two 100 subscribing witnesses.

CHARLES D. YOUNG.
